O.S. 2375

Amos Gearlin of Schuylerville N.Y.
Letters Patent No. 2375. Dated Aug. 7, 1866.
Design for "Metallic Armour for Boots & Shoes,"

The Schedule referred to in these Letters Patent and making part of the same.

To all whom it may concern.

Be it known that A. Amos Gearlin of Schuylerville in the County of Schuylerville and State of New York have invented certain new and useful Designs for "Metallic Armour for Boots and Shoes" and do hereby declare that the following is full, clear, and exact description of the same, reference being had to the accompanying drawing and the letters of reference marked thereon making a part of this Specification.

Fig. 1. represents the Armour for the left foot.

Fig. 2. represents the Armour for the right foot.

My invention is constructed of Iron, Steel, Brass, or other suitable metal and is either cast or wrought. It consists in a series of metal bars *a*, placed slightly in an oblique position, and running parallel to each other. These bars are connected to each other near their centers by the strips *b*, and are provided with openings *c*, at the centre and each end for the purpose of passing the screw by which the design is attached to the bottom of the sole of the Boot or Shoe. The forward end of the design is rounded to correspond with the shape of the foot and the oblique direction of the bars *a*, form a plate *d*, at the end so that the metal is larger under the large toe of each foot. At the rear end of the armour or the last bar *d*, is made convex in form and longer than the other bars. It will be perceived that this armour is to be placed on the sole of the Boot or Shoe just forward of the shank, and is consequently made wider at the rear end than at the toe, bar *d*, being made in the form shown to make a neat device to fit snugly upon the bottom of the sole.

Des. 2375

2

Having thus fully described my invention, what I claim as
new and desire to secure by Letters Patent is,

The Design for Metallic Armor for Boots or Shoes, as herein more particularly described,

As evidence that I claim the foregoing, I have hereunto set my hand in
the presence of two witnesses.

Wm H. Sidney,
H. Brewster,
